UNITED STATES PATENT OFFICE.

LOUIS CADENEL, OF PARIS, FRANCE.

ELECTRICALLY-CONTROLLED LOCK.

1,165,943.

Specification of Letters Patent.

Patented Dec. 28, 1915.

Application filed March 12, 1914. Serial No. 824,314.

To all whom it may concern:

Be it known that I, LOUIS CADENEL, a citizen of the French Republic, residing at Paris, France, have invented certain new 5 and useful Improvements in Electrically- Controlled Locks, of which the following is a specification.

The present invention relates to an electrically controlled keyless lock and particularly one of the type which can be operated by a switch provided with secret combinations and arranged to operate an alarm for all erroneous combinations; as an example of this type, I will refer to Leduc's French 15 Patent No. 433598, dated 25th August 1911. The lock has no opening, cannot be picked, and its mechanism is such that it is impossible to operate the bolt without the electric current.

20 The annexed drawing illustrates the invention.

Figure 1 is a plan of the inside, the parts being in the position allowing movement of the bolt. Fig. 2 is a partial view showing 25 the position of the parts when the door, on which the lock is secured, is closed and the bolt locked. Fig. 3 is a similar view to Fig. 1, showing the bolt free. Figs. 4 and 5 are elevations on a larger scale respectively 30 showing the position of the locking plate for the bolt when the latter is locked and when it is free. Fig. 6 is a plan of Fig. 4. Fig. 7 is a section on line A—A of Fig. 6.

As shown in Fig. 1, the lock comprises a 35 rectangular casing inclosing the various parts of the device. The face *a* of this casing has three openings, one *b* for the passage of the electric wires, another *c* for the passage of a rod *A* provided with a spring *d* and a third *e* for the passage of a rod *B* governed by a spring *f*.

On the inner face of wall *g* is fixed a square support *h* for guiding the rod *A* while giving it sufficient play to be displaced 45 laterally (that is, down from the positions shown in Figs. 1, 2 and 3).

The wall *i* of the casing has an opening for the bolt *P* and serving as a guide for the same. To set the lock and allow the bolt *P* 50 to lodge in the staple when the door is shut it is sufficient to push the button *b^t* of the rod *A* from left to right (from the position shown in Fig. 3 to that of Fig. 1) whereby a tooth *k* of this rod engages a tooth *l* of an eccentric or cam member *l'* mounted on a

lever *m* and oscillatable around a pin *n*, said member being under the action of the spring *s*. As the rod *A* moves toward the right, the spring *D* allows it to yield downwardly to a sufficient extent to clear the tooth *l*, but 60 immediately after the tooth *k* has passed to the right of the tooth *l*, the spring *D* pushes the rod *A* up again. The spring *d* being tensioned the two teeth remain in engagement under the action of the 65 plate spring *D* acting on the rod *A* and which holds the tooth *k* firmly engaged with tooth *l* and in this position preventing any release of the bolt by the action of blows or jars. The lever *m* being influenced by the 70 action of spring *d* can abut against the extremity of a lever *o* oscillating around the point *p*, this lever tends to move away from the wall *a* of the lock by the action of a spring *q*, but this movement is limited by an 75 abutment *r*. It can be seen that with the parts in this position the bolt *P* is movable and when shutting the door, it moves into the lock and out again to engage in the staple directly the door is closed. By switch- 80 ing on the electric current, the electromagnets *E¹*, *E²*, attract their respective armatures *S¹*, *S²*, (the former rigid with the lever *m*) and the lever *m* is thus liberated. The 85 tooth *k* under the action of the spring *d* draws the lever *m* which turns around the pin *n* and the abutment *t* of the rod *A* draws the abutment *u* of the rod *B*, and the bolt *P* is drawn into the interior of the lock. As 90 soon as the tooth *l* is free the spring *s* draws the lever *m* downward, that is to say, toward the wall *g* of the lock. In this position (Fig. 95 3) the bolt *P* remains always maintained in the interior of the lock by the distended spring *d*. To set the lock again it is sufficient to push the button *b^t* from left to right and proceed as previously described.

The armature *S²* of the electromagnet *E²* turning around the point *v* is provided with a copper spring *w* which tends to push it toward the left directly the action of the current ceases. Further this armature has a shoulder *x* on which the armature *S¹* engages. This device is for the purpose of preventing the armature *S¹* from moving 100 toward the electromagnet *E¹* and of releasing the lever *m* which would free the spring *d* and open the lock without the current 105 traversing the electromagnets. In effect if means were not provided for locking the 110

armature S¹, a violent blow on the door or any other analogous cause might effect the opening of the lock. By the combination of these two inter-engaging armatures fraudulent opening is impossible.

In order to prevent any fraudulent attempt to open the lock by pressure on the beveled face of the bolt P, the extremity of the rod A is provided with a steel plate or dog 1 having the particular shape shown in Figs. 4 and 5; this dog is housed in a slot suitably formed in the end of the rod A, is mounted to turn on a pin 2 and reduced at its extremity 3 by which extremity it rests on a small coil spring 4 conveniently guided and housed in a recess 5. The extremity 6 of the dog 1, forms a pawl arranged to abut against the shoulder 7 of a tappet 8 fixed to the bar B of the bolt P.

20 A block 9 can slide on the end of the rod A and is automatically brought into suitable position to maintain the dog 1 lowered or raised according as the bolt P is locked or unlocked. The block 9 is arrested at the 25 extremity of the rod A by the nose 11 of the dog 1, which serves as an abutment for the bolt and prevents the block 9 from sliding off the end of the rod at the time of electrical release of the bolt which pushes the member 30 9 to its initial position.

In Figs. 1 and 5 the block 9 is at the free end of the rod A and maintains the dog 1 raised, which allows of setting the lock without the said block 9 moving relatively to the rod A. At this moment by closing the door, the bolt P by means of the tappet 8 on the bar B pushes back the block 9, it being understood that the bolt is forced inward owing to its beveled 40 end engaging the keeper or the like; the block 9 is thus brought back to the position shown in Figs. 2 and 4, releasing the dog 1 so that its end 6 can move downward under the influence of the spring 4. Since however, 45 at the beginning of this movement toward the left, the tappet 8 is to the left of the nose 11 (Fig. 5), the tappet and dog do not come into coöperation during such movement toward the left. As soon as the door reaches 50 the fully-closed position, the spring f projects the bolt P into the opening of the keeper (this being the position shown in Fig. 2), causing the inclined surface of the tappet 8 to engage the nose 11 and partially 55 lift the dog 1 so that said surface will pass from a position at the left of the nose 11, to a position at the right of said nose, and the dog 1 falling into the position shown in Fig. 4 engages the shoulder 7 of the tappet 8 and 60 locks the bolt. In this position the block 9 further contributes to maintain the dog 1 in its inclined or locking position, that is to say, it strengthens the action of said plate and renders it absolutely efficacious and reliable.

What I claim as my invention and desire to secure by Letters Patent of the United States is:—

1. In an electrically controlled lock, the combination of a casing, a bolt, a rod integral with said bolt, a setting member projecting to the outside of said casing, a tooth thereon, a pivoted member, a tooth thereon with which the tooth of said setting member is adapted to engage, means for holding said teeth in engagement or releasing them to lock or release the bolt and electrically operated means for controlling said means. 70

2. In an electrically controlled lock, the combination of a casing, a bolt, a rod integral with said bolt, a setting member projecting to the outside of said casing, a tooth thereon, a pivoted member, a tooth thereon with which the tooth of said setting member is adapted to engage, means for holding said teeth in engagement or releasing them to lock or release the bolt, electrically operated means for controlling said means, and additional means for locking said bolt. 80

3. In an electrically controlled lock, the combination of a casing, a bolt, a rod integral with said bolt, a setting member projecting to the outside of said casing, a tooth thereon, a pivoted member, a tooth thereon 95 with which the tooth of said setting member is adapted to engage, a lever co-axial with said pivoted member, a spring governing said pivoted member, a pivoted angle member, one arm of which is adapted to coact with said lever, and electrically operated means acting on the other arm of said angle member. 90

4. In an electrically controlled lock, the combination of a casing, a bolt, a rod integral with said bolt, a setting member, a tooth thereon, a pivoted member, a tooth thereon with which the tooth of said setting member is adapted to engage, a lever co-axial with said pivoted member, a spring 105 governing said pivoted member, a pivoted angle member, one arm of which is adapted to coact with said lever, an electromagnet 110 acting on the other arm of said angle member, a second lever adapted to control the movement of said last mentioned arm and a second electromagnet controlling said second lever. 115

5. In an electrically controlled lock, the combination of a casing, a bolt adapted to slide therein, a spring governed rod integral with said bolt, a spring governed setting bar, one end of which projects through said casing, means for guiding said rod and said bar, means for operating said rod by the 120 movement of said bar, a spindle, a cam member mounted to turn thereon, a tooth on said cam member, a tooth on said bar adapted to be engaged with said cam tooth, a rocking lever mounted on said spindle and fixed to 125 130

said cam member, means for locking said teeth in engagement to lock or releasing them to free the bolt, electrically operated means for controlling said means and additional means for locking said bolt.

6. In an electrically controlled lock, the combination of a casing, a bolt adapted to slide therein, a spring governed rod integral with said bolt, a spring governed setting bar, 10 one end of which projects through said casing, means for guiding said rod and said bar, means for operating said rod by the movement of said bar, a spindle, a cam member mounted to turn thereon, a tooth on said 15 cam member, a tooth on said bar adapted to be engaged with said cam tooth, a rocking lever mounted on said spindle and fixed to said cam member, means for holding said teeth in engagement to lock the bolt or releasing them to free the bolt, a dog pivoted 20 in a slot in the end of said bar, a spring, a tappet on said rod with which said dog is adapted to engage by the action of said spring and an automatically sliding block 25 mounted on said bar adapted to release said dog from engagement with said tappet.

7. In a lock, a casing, a bolt, a spring for projecting it into the operative position, a dog adapted to lock said bolt in its operative 30 position, means, operated by the retractive movement of the bolt which occurs as said bolt approaches the closing position, for setting said dog to a position in which it may lock the bolt upon its springing home to the locking or operative position, and means for 35 releasing the bolt.

8. In a lock, a casing, a bolt, a spring for projecting said bolt into the operative position, a dog movable into and out of the path 40 of said bolt, a slide arranged to be engaged by said bolt and to be moved thereby inward when the bolt is retracted as it approaches its operative position, to bring said slide from a position in which it keeps the dog in 45 its inactive position to one in which the dog

is caused to project into the path of the bolt to hold it positively in the locked position when it snaps home, and means for releasing the bolt.

9. In a lock, a casing, a bolt, a spring for 50 projecting the bolt into the operative position, a setting member movable in a direction parallel with the bolt, elastic means for normally causing the bolt and setting member to move in unison, yet allowing an independent movement of the bolt, locking means coöperating with said setting member, a dog carried by said setting member, and movable into and out of the path of said bolt, a slide movable along said setting member and controlling said dog, said slide being in the path of the bolt so that when the bolt moves independently of the setting member as the bolt approaches its operative position, the slide will be brought from a 55 position in which it holds the dog out of the path of the bolt, to one in which the dog is caused to project into the path of the bolt to hold it positively in the locked position when it snaps home, and means, coöperating with 60 the locking means of the setting member, for releasing said setting member and the bolt.

10. In a lock, a casing, a bolt, a spring for projecting the bolt into the operative position, a setting member movable in a direction parallel to the path of the bolt, elastic means for normally causing the bolt and setting member to move in unison, yet allowing an independent retractive movement of the bolt, locking means coöperating with said 75 setting member, and means, coöperating with said locking means, for releasing said setting member and the bolt.

In witness whereof I have signed this specification in the presence of two witnesses.

LOUIS CADENEL.
